CLAIM

The ornamental design for a frequency converter, substantially as shown and described.

DESCRIPTION

FIG. 1 is a front, right side and top perspective view of a frequency converter comprising a new, original and ornamental design;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.
